UNITED STATES PATENT OFFICE.

CARL F. SKOOG, OF SOUTH BEND, INDIANA.

CLINKER TONGS.

Application filed July 12, 1922. Serial No. 574,563.

To all whom it may concern:

Be it known that I, CARL F. SKOOG, a citizen of the United States, residing at South Bend, in the county of St. Joseph and State 5 of Indiana, have invented a certain new and useful Improvement in Clinker Tongs, of which the following is a full, clear, concise, and exact description, reference being had to the accompanying drawings, forming a 10 part of this specification.

My invention relates to clinker tongs and more particularly to a device of this character adapted for insertion through the front fire door of a furnace, etc., and adapted to 15 be extended down into the fire box so that the co-operable fingers at the end of the tongs may be actuated to grip the clinkers so that they may be lifted out of the fire pot.

For a better understanding of my invention reference is to be had to the accompanying drawings in which—

Fig. 1 is a side elevation of my clinker tongs with the handle construction broken away;

Fig. 2 is a bottom view of Fig. 1; and Fig. 3 is a sectional view along the line 3—3 of Fig. 1.

Referring more in detail to the device shown, it comprises a suitable head A having laterally extending hook shaped fingers 5—6, preferably two in number, although, of course, more may be used if desired. These fingers are preferably in the form of a forked shaped extension connected at the 35 cross piece 7. The head A is hollowed out as indicated by the dotted line 8 and has a pair of depending ears 9 between which a movable finger 10 is pivotally supported. The operating end 10' of the finger extends 40 up into the hollow of the head and is pivotally connected to an operating rod 11 which extends back through the tubular handle 12. This handle is secured to the head preferably by threading into a neck extension 13. 45 The head A and its integral parts are preferably constructed of cast malleable iron although, of course, not limited to this material.

An operating member is supplied in the 50 form of a slidable sleeve or handle 14. The operating handle 14 is secured to the operating rod 11 by means of a cap 15 which threads onto the sleeve 14 and through which the rod 11 extends. The rod is secured to the cap by means of a nut 16 on the inside

and a nut 17 on the outside with the ring member 18 clamped between, this ring serving as an operating handle or by which the device may be hung on the wall.

The construction shown may be very 60 readily assembled, the movable finger 10 and the rod 11 being first connected together by the pivot pin 19. This rod 11 may then be inserted through the forked fingers 5—6 and through the hollow of the head A into the 65 tubular handle 12, after which the finger bearing bolt 20 is inserted through the ears 9 and the finger 10 and clamped in position. The operating handle 14 with its cap 15 is then slipped over the free end of the handle 70 12 and rod 11 against the nut 16, after which the ring 18 and nut 17 are put in place. The device may just as readily be taken apart.

In connection with the tubular handle 12, this of course, may be made of any desired 75 length depending upon the use to which the device is to be put. Ordinarily a handle about twenty-four to thirty inches long will take care of the usual furnace or fire place.

This handle 12, however, may be extended 80 into great lengths so that the tongs may be used also for removing articles from high shelves where they may be gripped between the fingers.

In the operation of the fingers when used 85 for removing clinkers from the usual residential boiler or furnace, the tong head is inserted at an angle down through the fire door opening, the operator gripping the handle 12 in one hand and the operating 90 handle with the other and extending the fingers into their open position. The clinkers are then raked up loose by the rigid laterally extending fingers 5 after which the handle 14 is pulled outwardly thereby closing 95 the fingers to grip the clinker so that it may be readily removed through the fire door.

What I claim as new and desire to secure by United States Letters Patent is:

1. In a clinker tongs of the character described, a hollow head having a solid neck and hook shaped forked end extending laterally from one end thereof and ears depending from an open side of the head with a threaded socket at the other end, a tubular 100 handle extending from and threaded into the socket of the head, a laterally positioned finger extending between said ears into the head and pivoted to said ears, a rod extending through said handle ending in the hol- 110

low head and pivotally connected to the finger inside the head, and an operating handle for said rod.

2. In a clinker tongs of the character described, a hollow head having a hook shaped finger extending laterally from one end thereof and ears depending from an open side, a tubular handle extending from the other end of the head, a laterally positioned finger extending between said ears into the head and pivoted to said ears, a rod extend-

ing through said handle into the hollow head and pivotally connected to the finger inside the head, the hollow in said head being so shaped and said ear pivots so positioned as to permit insertion and removal of the finger and attached rod through the head. 15

In witness whereof, I hereunto subscribe my name this sixth day of May A. D., 1922.

CARL F. SKOOG.
